Primary Examiner — Vy N Koenig(74) *Attorney, Agent, or Firm* — Jacob M. Ward; Ward Law Office LLC(57) **CLAIM**

The ornamental design for a cleaning blower nozzle for digital camera sensor, as shown and described.

DESCRIPTION

FIG. 1 is a top perspective view of a cleaning blower nozzle for digital camera sensor showing my new design;

FIG. 2 is a bottom perspective view of the cleaning blower nozzle for digital camera sensor shown in FIG. 1;

FIG. 3 is a top plan view thereof; and,

FIG. 4 is a right side elevational view thereof; the front, rear and left elevational side views are identical to the right side. The broken lines in the drawings are for the purpose of illustrating environmental structure that forms no part of the claimed design.
